UNITED STATES PATENT OFFICE.

HENRY A. DE LA HOOKE, OF TOLEDO, OHIO.

INDICATOR-LOCK FOR CAR-DOORS.

SPECIFICATION forming part of Letters Patent No. 340,427, dated April 20, 1886.

Application filed August 31, 1885. Serial No. 175,778. (No model.)

To all whom it may concern:

Be it known that I, HENRY A. DE LA HOOKE, of Toledo, in the county of Lucas and State of Ohio, have invented new and useful Improvements in Indicator-Locks for Car-Doors, of which the following is a specification, reference being had to the accompanying drawings, and to the letters of reference marked thereon.

The invention is specially intended for use as a freight-car lock.

The invention is so constructed that a number is automatically registered each time the lock is opened, in order that any tampering with the freight in the car to which the lock is attached may be discovered. On closing the lock a certain number is exhibited, which indicates the station at which the lock was closed, and each time it is opened after leaving such station the automatic registration occurs, so that when the car reaches its destination the agent may be able to determine exactly how many times the lock has been opened during the transit of the freight, and where such opening occurred, and thereby locate any tampering with the freight.

In the accompanying drawings, Figure 1 is a vertical sectional elevation of my improved permutation-padlock. Fig. 2 is an exterior elevation. Figs. 3 and 4 are vertical transverse sections, as hereinafter described. Fig. 5 is a view of a detail.

Similar letters of reference indicate similar parts in the respective figures.

A is the case of the padlock, of which a is the shackle, pivoted at a'. The locking end of the shackle is provided with a hook, b, and a notch upon the opposite side, represented by c. The hook b is confronted by a numbered wheel, B, provided upon its inner face with teeth d. A detached view of the wheel is shown in Fig. 5. The wheel is provided with a spring, b', a pawl, b'', and teeth b''', by means of which the wheel is held against turning in but one direction.

C is a dog or detent operated upon by a spring, c', said dog or detent having a projection, e, which fits within the notch c of the shackle a. The shackle a is provided with a spring, a'', the effect of which is to force the shackle upward when released. The key-hole, which is adjacent to the dog or detent C, is shown by f.

Bearings g g' g'' g''' are provided within the casing, preferably forming a part thereof, and which support or aid in supporting the inner ends of shafts bearing the numbered wheels D, E, and F.

G is a shaft having its outer bearing in the casing A and its inner bearing at g, and carrying a toothed wheel, h.

H is a similar shaft having its outer bearing in the casing A and its inner bearing at g', said shaft carrying the numbered wheel D. Concentric with the shaft H, and having its bearings in g'g'', is a shaft, H', carrying the numbered wheel E and the toothed wheel h', which gears with the toothed wheel h of the shaft G; also concentric with the shaft H, and having its bearings in g''g''', is a shaft, H'', carrying the numbered wheel F, to which is attached the toothed wheel h''. A shaft, I, also having its outer bearing in the casing A and its inner bearing in g''', carries a toothed wheel, h''', which gears with the wheel h'' upon the shaft H''. Each of the shafts is provided outside of the casing A with a knob or button, i, by means of which it may be revolved.

At the inner extremity of the pivoted end of the shackle a is an inclined tongue, k, Fig. 4, and at the lower part of the casing is secured a spring-bar, K, having small teeth or corrugations k', k'', and k''', which, at proper times, are intended to engage with similar teeth or projections, l' l'' l''', upon the shafts G, H, and I, respectively.

In operation, supposing the lock to be closed, the hook b is in the position shown in Fig. 1—that is to say, the projection e of the dog or detent C is within the notch c of the shackle a. The projection b is clear of the teeth d of the wheel B. The teeth or projections k' k'' k''' of the spring-bar K are in gear with the teeth l' l'' l''' of the shafts G, H, and I. Supposing the car has been closed and the lock adjusted at a station numbered, say, 123, the numbered wheels D, E, and F, having (of course before the lock was closed) been adjusted by hand, so that the numbers 1, 2, and 3 shall be exhibited, as shown, through the openings m, n, and o of Fig. 2, and the wheel B adjusted so as to indicate, say, No. 1 at the opening p, it is apparent that should the lock be opened by inserting the key and pushing back the dog or detent C, the shackle a cannot rise by the ac-

tion of the spring a'' without the hook b of the lever coming in contact with a tooth, d , of the wheel B , and causing it to revolve one tooth, and thus indicate another number as the number 2 at the opening p , Fig. 2.

The openings $m n o p$ are suitably closed by glass to exclude dust.

Normally, and when in the position shown in Fig. 1, the hook b is sprung back or out of contact with the teeth of the wheel B , but upon the release of the lever the hook b , moving upward, comes in contact with the teeth as stated, and consequently registers a number through the medium of the wheel B . It will also be seen by reference to Fig. 4 that when the shackle a is closed the inclined tongue k thereof presses the teeth of the spring-bar K into gear with the teeth of the shafts G , H , and I , so that said shafts and their train of wheels are locked whenever the lock is closed.

By reference to Fig. 3 it will be seen that when the shackle a is lifted the teeth of the spring-bar and shafts are automatically detached, this being effected by the elasticity of the bar K .

It will be understood that the numbers of the wheels D , E , and F are to be adjusted by

the authorized agent at any station in the line of travel of the car, and that the number indicated at the openings $m n o$ will always show what agent has last opened the lock. Thus there is a concerted action between the numbered wheels D , E , and F , and the numbered wheel B .

Having described my invention, I claim—

1. In an indicator-lock, the combination, with the shackle a , provided with a hook, b , and the spring detent or dog C , of the toothed wheel B , whereby, when the said shackle is released, the wheel may be revolved thereby, substantially as set forth.

2. In an indicator-lock, the combination, with the hooked shackle a , provided with the tongue k , and the toothed wheel B , of the shafts G , H , and I , having gearing, the geared and numbered wheels D , E , and F , and the spring-bar K , substantially as set forth.

In testimony whereof I hereunto set my hand and seal this 18th day of May, A. D. 1885.

HENRY A. DE LA HOOKE. [L. s.]
